TERMINAL STUD RECEIVING SOCKET FOR A WHEEL CHANGING TOOL FOR AUTOMOBILES

David Ehler, 9 Manor Road, Lake Zurich, Ill. 60047

Filed Sept. 11, 1973, Ser. No. 396,215

Term of patent 14 years

Int. Cl. D8—05

U.S. Cl. D8—31

FIG. 1 is a side elevational view of the terminal stud receiving socket for a wheel changing tool for automobiles.

FIG. 2 is a top view of FIG. 1.

FIG. 3 is a fragmentary bottom view of FIG. 1.

FIG. 4 is an enlarged elevation view of the stud receiving socket as shown in FIG. 1.

FIG. 5 is an enlarged view of the stud receiving socket as shown in FIG. 2.

FIG. 6 is an end view taken along the lines 6—6 of FIG. 5.

The handle for the tool is shown in broken lines for illustration of the environment.

I claim:

The ornamental design for a terminal stud receiving socket for a wheel changing tool for automobiles, as shown and described.
